UNITED STATES PATENT OFFICE.

FRED E. BROWN, OF POMONA, CALIFORNIA.

DESIGN FOR A LICENSE-PLATE HOLDER.

Application filed April 4, 1927. Serial No. 21,450. Term of patent 3½ years.

To all whom it may concern:

Be it known that I, FRED E. BROWN, a citizen of United States, residing at Pomona, in the county of Los Angeles and State of California, have invented a new, original, and ornamental Design for License-Plate Holders, of which the following is a specification, reference being had to the accompanying drawing, forming part thereof.

I claim:

The ornamental design for a license plate holder, as shown.

FRED E. BROWN.
